UNITED STATES PATENT OFFICE.

JAMES M. TRIGGS AND WILLIAM D. REDRUP, OF HUNTINGTON, INDIANA, ASSIGNORS TO THE MAJESTIC COMPANY, OF HUNTINGTON, INDIANA, A CORPORATION OF INDIANA.

DUPLEX-REGISTER BOOT.

1,310,812.

Specification of Letters Patent. Patented July 22, 1919.

Application filed March 22, 1918. Serial No. 223,968.

To all whom it may concern:

Be it known that we, JAMES M. TRIGGS and WILLIAM D. REDRUP, citizens of the United States, and residents of Huntington, in the county of Huntington and State of Indiana, have invented a certain new and useful Duplex-Register Boot; and we do hereby declare the following to be a full, clear, and exact description of the invention, 5 such as will enable others skilled in the art to which it appertains to make and use the same, reference being had to the accompanying drawings, and to the characters of reference marked thereon, which form a part 10 of this specification.

This invention relates to hot air heating systems, and particularly to those of the type employing combined hot air outlet and cold air return registers, as disclosed in 20 United States Letters Patent No. 1,152,864, issued September 7th, 1915, to James M. Triggs.

The object of our invention is the provision of an improved boot for use in connection with registers of the class described, 25 which boot is simple and inexpensive in construction, capable of being easily and quickly installed and adapted to conduct the hot air to and the cold air from registers of 30 the duplex type.

The invention is fully described in the following specification, and while, in its broader aspect, it is capable of embodiment in numerous forms, a preferred embodiment 35 thereof is illustrated in the accompanying drawings, in which,—

Figure 1 is a perspective view of a boot embodying the invention, and Fig. 2 is an enlarged central vertical section thereof in 40 connection with a register of the duplex type.

Referring to the drawings, 1 designates a register of the duplex type, having the center hot air outlet passage 2 and the two cold 45 air inlet passages 3, 3 at opposite sides of the hot air passage. This register is customarily mounted on the floor 4 over an opening therein, and a boot 5, embodying the present invention, is disposed below the floor with 50 its upper end extending into and filling the floor opening.

The boot is provided interiorly with the

downwardly extending center passage 6 and with the opposite side passages 7, 7, which register at their upper ends respectively 55 with the center hot air passage 2 and the side cold air passages 3, 3 of the register in a manner to form continuations of the register passages. The center or hot air passage 6 of the boot has its lower end terminating 60 short of the bottom of the boot and closed to the passages 7 and is provided in one of its outer side walls with an outwardly flanged opening 8 with which a pipe leading from a furnace or other suitable source of hot air 65 supply may be connected. The side cold air passages 7, 7 of the boot extend below and communicate under the bottom of the center passage 6 and have a common outwardly flanged outlet opening 9 in the bottom 70 of the boot, which flange is intended to be connected by a pipe to the cold air inlet of a furnace. The bottom 10 of the boot extends downward in conical restricted form to the opening 9.

The walls 11 forming the hot air passage 6 are of double form, in the present instance, with an interposed asbestos lining to prevent dissipation of the heat through said walls.

It is evident that we have provided a boot 80 of unitary construction for use in connection with registers of the duplex type, which boot is adapted to connect the respective hot and cold air passages of the register with the hot and cold air pipes of a furnace in a 85 simple, efficient and economical manner, and that it is capable of being easily and quickly installed.

We wish it understood that our invention is not limited to any specific construction, 90 arrangement or form of the parts, except in so far as such limitations are specified in the claim.

Having thus described our invention, what we claim as new, and desire to secure by Letters Patent, is,—

A boot of the class described, comprising a casing open at its top and having a downwardly converging bottom with an outlet opening at its center, partitions disposed in 100 spaced relation transversely of said casing and connected at their lower ends in vertically spaced relation to said bottom opening, said partitions being joined at their side

edges to opposite side walls of said casing to coöperate with the casing to form a central passage and opposite side passages all open at their tops with the side passages extending under the bottom of the central passage and communicating with said bottom opening, said central passage having a side

inlet opening near its bottom intermediate said side passages.

In testimony whereof we have hereunto signed our names to this specification.

JAMES M. TRIGGS.
WILLIAM D. REDRUP.
